CHAUNCEY B. EARNHEART, OF INDIANAPOLIS, INDIANA, ASSIGNOR TO SAFETY FIRST DEVICES COMPANY, OF INDIANAPOLIS, INDIANA, A CORPORATION OF INDIANA.

AIR-VALVE STRUCTURE.

1,305,266.

Specification of Letters Patent.

Patented June 3, 1919.

Application filed July 26, 1918. Serial No. 246,875.

To all whom it may concern:

Be it known that I, CHAUNCEY B. EARNHEART, a citizen of the United States, and a resident of Indianapolis, county of Marion, 5 and State of Indiana, have invented a certain new and useful Air-Valve Structure; and I do hereby declare that the following is a full, clear, and exact description thereof, reference being had to the accompanying 10 drawings, in which like numerals refer to like parts.

This invention relates to air valves for pneumatic tires and the like, especially those having means for indicating the air pressure within the tire, and is an improvement over the device shown in my former application, 15 Serial No. 96,119, filed May 8, 1916.

One object of the invention is the provision of a valve mechanism for positively 20 closing communication through the valve stem, to prevent leakage therethrough.

A further feature of the invention is in the provision of means cooperating with the casing or sleeve of the valve structure for 25 forcing the valve firmly into engagement with its seat.

A further feature of the invention is the provision of means for attaching the part employed for engagement with the sleeve of 30 the valve structure, with the parts carrying the valve proper, so that said part may have rotating movement thereon but be held against longitudinal movement thereof.

A further feature of the invention is the provision of a seal between the valve stem proper and the casing therefor, and the parts carrying the valve proper and the casing.

A further feature of the invention is the provision of means for connecting a spirally 40 wound tension spring to the valve stem proper and to the stem carrying the valve proper, so that said valve may have sufficient movement, independently of the spring, to open and close the port through the valve stem without influencing the tension spring.

Other objects and advantages will be hereinafter more fully set forth and pointed out in the accompanying specification.

In the accompanying drawings which are 50 made a part of this application, Figure 1 is a central longitudinal sectional view through the valve structure, showing the parts in closed position, and Fig. 2 is a similar view, showing the parts of the valve structure in 55 open position.

Referring to the drawings, 1 indicates the valve stem proper, which is provided at one end with a head 2 for engagement with parts of the pneumatic tire (not shown), while the upper end portion of the valve stem is 60 reduced and the end face thereof tapered to provide a seat 3, the valve stem having a central bore 4 extending from end to end thereof and through the head 2.

A portion of the body of the valve stem 1 65 is exteriorly threaded, as shown at 5, with which engage threads 6 in the end of a sleeve 7, the interior of the sleeve 7 immediately above the threaded portion 6 having a tapered shoulder 8 for engagement with a 70 packing 9, of any suitable material, said packing being in the form of a ring, and entered in a peripheral recess 10 formed in the valve stem 1, the rear wall of the recess being likewise tapered coincident to the tapered 75 shoulder 8, whereby the sleeve will have a wedging action against the packing.

Longitudinally movable in the opposite end of the sleeve 7 is a plunger 11 which has a stem 12 at its inner end, and extending 80 transversely through the stem 12 at a point a distance beyond the inner end of the plunger 11 is a port 13 with which communicates a bore 14 extending longitudinally of the plunger, the outer end of the bore 14 being enlarged to receive the usual form of check 85 valve 15. The extreme inner end of the stem 12 is threaded into engagement with an extension 16, the inner end of which is provided with a socket 17 in which is placed any 90 suitable form of packing 18, preferably of rubber, said packing being adapted to engage the seat 3 at the inner end of the stem 1, and when pressed against said seat, to close communication through the bore 4 and 95 prevent the escape of fluid from the valve stem.

The outer end of the plunger 11 projects a distance beyond the end of the sleeve 7, and is exteriorly threaded to receive an air 100 pump attachment so that air may be pumped through the valve structure, the packing 18 being held firmly seated on the inner end of the valve stem 1, through the medium of a collar 19 which threads on to a lip 20 at the 105 end of the sleeve 7. The collar 19 is first turned over the threaded portion of the plunger 11, a prescribed distance, when the outer end of the collar 19 is bent inwardly to form a ring 21 which fits in a groove 22 surround- 110

ing the projecting end of the plunger 11, and as the threads within the collar are at this time disengaged from the threads on the plunger 11, the collar 19 has a free rotating movement on the plunger, but is held against longitudinal movement thereon by the ring 21 entering the groove 22. This causes the plunger 11 and parts attached thereto, to travel inwardly when the free end of the collar 19 is turned on to the lip 20 of the sleeve 7, and consequently forces the packing 18 firmly against the seat 3 at the inner end of the valve stem 1.

The plunger 11 is held against rotation within the sleeve 7 by providing a slot 23 in the outer face of the plunger in which travels a knob 24, formed on the inner face of the sleeve 7, said knob also serving to limit the longitudinal movement of the plunger. The exterior face of the plunger 11 is provided with graduations 25 which are employed for indicating the pressure within the tire or other device to which the valve structure is attached, said graduations being read as they successively register with the end of the sleeve 7.

In order to indicate correctly the amount of pressure within the tire or object to which the valve structure is attached, a spirally arranged spring 26 is introduced in the sleeve 7 and attached at one end to the inner end of the valve stem 1, while the opposite end thereof is attached to a band 27 surrounding the stem 12, between the end of the extension 16 and the end of the plunger 11 proper, the exterior surface of the band 27 and the inner end of the valve stem 1 having spirally arranged channels so that the spiral coils of the spring 26 may be turned thereon. The band 27 is loosely mounted on the stem 12 and is so arranged that the extension 16 can move away from the end of the valve stem 1 a sufficient distance to permit fluid to pass into or out of the bore in the valve stem before it directs pressure against the band. Leakage around the plunger 11 is prevented by introducing a packing 28 within the sleeve 7 at the inner end of the plunger 11, said packing being held in position by means of a nut 29 which threads on to the stem 12, said packing 28 being beyond port 13 so that the fluid entering or leaving the valve structure will pass directly into the cavity in the sleeve 7 and from thence into the bore 4 of the valve stem 1.

In operating this form of device, a fluid is pumped into the upper end of the plunger 11 from whence it passes downwardly through the check valve 15, bore 14, through the port 13 and thence into the opening in the sleeve 7, and thence through the bore 4 into the object to which the valve structure is attached. As the pressure increases, the plunger 11 is forced upwardly so as to suc-

cessively register the graduating marks 25 with the upper end of the sleeve 7, said graduations denoting the pounds pressure of the fluid. As soon as the desired pressure is obtained, the plunger 11 is manually forced inwardly and the collar 19 threaded on to the lip 20, this action forcing the packing 18 against the seat 3 of the valve stem 1, thus completely closing communication through the bore 4. 75

At such time as it is desired to again replenish the object to which the valve structure is attached, with fluid, the collar 19 is unscrewed from the lip 20 so as to unseat the packing 18 from the end of the valve 80 stem 1, as shown in Fig. 2, and it will be readily seen that so long as the end of the collar 19 is resting against the end of the lip 20, it will be impossible to lower the packing 18 against its seat until such time as the collar 19 is rotated to cause the threads 85 therein to engage the threads of the lip.

In assembling the parts of the valve structure together, the packing 28 and nut 29 or other securing means for the packing are introduced into position, after which the band 27 is slipped over the stem 12 and the extension 16 carrying the packing then screwed on to the end of the stem 12. One end of the tension spring 26 is engaged with 90 the band 27 and the opposite end then engaged with the end of the valve stem 1.

The plunger 11 and parts attached thereto are then introduced into that end of the sleeve 7 containing the threads 6 and moved 100 longitudinally through said sleeve until the threads 5 on the valve stem 1 engage the threads 6 of the sleeve 7, when the valve stem 1 is rotated to interlock the threads 5 and 6 and force the packing 9 against the 105 shoulder 8 of the sleeve. The collar 19 is then screwed on to the protruding end of the plunger 11 until the outer end thereof registers with the groove 22 in the periphery of the plunger, after which the extreme 110 outer end of the collar is crimped inwardly to form the ring 21 which enters said groove. The valve structure is then ready to be applied to use. By forming the valve structure in this manner, the parts are reduced 115 to a minimum so that the valve structure can be very cheaply constructed and far more readily assembled, and furthermore the collar resting upon the lip, when the collar is unscrewed therefrom, will form a 120 positive support for the plunger and parts attached thereto, which will prevent the packing at the inner end of the extension on the plunger from engaging its seat until such time as the collar is turned on to the 125 lip.

The invention claimed is:

1. In a valve structure, the combination with a valve stem having a bore therethrough, a seat at the inner end of the valve 130

stem, and a sleeve attached to the valve stem, of a plunger slidably mounted in the sleeve, an inwardly extending stem on said plunger, said latter stem having a transverse port, 5 and the plunger having a bore communicating therewith, a band loosely surrounding the plunger stem, a tensioning device having one of its ends secured to said valve stem and the opposite end to said band, and 10 means on the plunger stem for expanding said tensioning device when the plunger is moved outwardly.

2. In a valve structure, a sleeve, a plunger longitudinally movable in said sleeve, an 15 exteriorly threaded stem integral with said plunger of less diameter than the diameter of said plunger and forming a shoulder at the meeting point between the plunger and stem, said plunger and a part of said stem 20 having a longitudinal bore and the stem having a transverse bore therethrough communicating with the inner end of the longitudinal bore, a cup shaped packing having its horizontal portion surrounding said stem 25 and its vertical portion resting against the inner wall of the sleeve, said transverse bore being below said packing and a nut threaded on to the stem and pressing the horizontal portion of the packing against said shoulder.

30 3. In a valve structure, the combination with a valve stem, a plunger coöperating therewith, a stem carried by the plunger, an extension carried by said plunger stem, and a packing carried by the extension adapted 35 to control communication through the valve stem, of a tensioning spring having one of its ends attached to the valve stem, and means loosely mounted on the plunger stem to which the opposite end of the tensioning spring 40 is attached, said plunger stem having limited movement through said means whereby the packing may be engaged with or disengaged from its seat without affecting the tension of said spring.

45 4. In a valve structure, the combination with a valve stem having a seat at its inner end and a sleeve having a threaded lip at one end, of a plunger having a peripheral groove adjacent its outer end, means for attaching a packing to the inner end of the plunger and an interiorly threaded collar 50 adapted to thread on to said lip, the outer

end of said collar being bent inwardly and the inwardly bent portion entered into the groove in the plunger, whereby when the 55 collar is turned on to the lip the plunger will move the packing against the seat on the valve stem, and when turned off of said lip will elevate and hold said packing suspended a distance from the seat on the valve 60 stem.

5. In a valve structure, the combination with a sleeve having an exteriorly threaded lip at one end, of a plunger slidable in said sleeve and projecting beyond the end thereof 65 containing the lip, the extreme outer end portion of the plunger being threaded and that portion thereof adjacent the end of the sleeve having a groove of less diameter than the threaded portion, a collar having threads 70 on its inner end portion adapted to engage the threads of the lip to force the plunger inwardly, said collar having threads at its outer end portion of less diameter than the diameter of the threads at the inner end 75 portion, said second threads adapted to engage the threaded outer end of the plunger and move inwardly into registration with said groove when rotated, the outer end of said sleeve then being crimped inwardly and 80 entered in said groove for rotatably mounting the collar on the plunger and holding the same against longitudinal movement thereof.

6. In a valve structure, the combination 85 with a valve stem, and a plunger coöperating therewith, of a tension spring having one of its ends attached to the valve stem, and means loosely mounted on the plunger to which the opposite end of the tension spring 90 is attached.

7. In a valve structure, the combination with a valve stem and a plunger coöperating therewith, of a tension spring having one of its ends attached to the valve stem, and 95 means loosely mounted on the plunger to which the opposite end of the tension spring is attached, said plunger having limited movement through said loosely mounted means without affecting the tension of the 100 spring.

In witness whereof I have hereunto affixed my signature.

CHAUNCEY B. EARNHEART.
